UNITED STATES PATENT OFFICE

CHARLES FRIZELL, OF BOSTON, MASSACHUSETTS.

IMPROVEMENT IN STEP-LADDERS.

Specification forming part of Letters Patent No. **140,359**, dated July 1, 1873; application filed April 10, 1873.

To all whom it may concern:

Be it known that I, CHARLES FRIZELL, of Boston, in the county of Suffolk and State of Massachusetts, have invented new and useful Improvements in Step-Ladders, of which the following is a specification:

This invention relates to that class of ladders which are formed with flat steps instead of rungs, and which are usually made self-supporting by means of a hinged support at the back; and the invention consists in constructing the side or string pieces each of two parts or bars, placed parallel or nearly so to each other, and connected by rungs or bars, while lateral braces are inserted in such bars and connected with the steps. The sides or string pieces are also strengthened by a metallic tie, the ends of which are secured to the upper string-piece of the sides, while it is carried under one or more of the central steps, in order the better to economize its tensional strength, for the support of the side or string piece.

Figure 1 is a front elevation taken at the left of Fig. 2. Fig. 2 is a side elevation taken at the right of Fig. 1. Fig. 3 is a back elevation taken at the right of Fig. 2.

In the drawings, **A A** represent the side or string pieces, which are each composed of the two narrow bars **a a**, Fig. 2. **b b** are short ties or bars, which enter the bars **a a** and are firmly secured therein. **c c** are short panels secured between bars **a** at their respective

ends, and serve the purposes of symmetry, uniting the exposed ends of the bars and affording a broader bearing for the sides. **d d** are the lateral braces, the lower ends of which are secured in ties **b**, while the upper ends are secured in steps **c**. **f f** are metallic truss-rods, the ends of which are secured to the upper bar **a** by screws **g**, as shown in Figs. 1 and 2, while the rod is carried under the central step, as shown in Fig. 2, thereby producing the desired deflection of the rod to insure a tensional strain upon it when the weight upon the ladder is near the center. Fig. 3 represents the back support, which is hinged to the ladder, as shown in Figs. 2 and 3; but, as no claim is made thereto, a more definite description is not deemed necessary.

I desire to state briefly the advantages of my invention, which are lightness, great strength, durability, rigidity, and resistance to lateral and indirect pressure, with great economy in material required for its construction.

What I claim as my invention is—

1. The sides **A A**, when constructed with bars **a a** and tie-rods **b**, substantially as and for the purposes specified.

2. The combination and arrangement of tie-rods **b**, braces **d**, and steps **c**, substantially in manner as and for the purposes specified.

CHARLES FRIZELL.
